UNITED STATES PATENT OFFICE.

LOUIS F. BLUME, OF PITTSFIELD, MASSACHUSETTS, ASSIGNOR TO GENERAL ELECTRIC COMPANY, A CORPORATION OF NEW YORK.

SWITCH.

Application filed January 13, 1923. Serial No. 612,452.

To all whom it may concern:

Be it known that I, LOUIS F. BLUME, a citizen of the United States, residing at Pittsfield, county of Berkshire, State of Massachusetts, have invented certain new and useful Improvements in Switches, of which the following is a specification.

My invention relates to switches. The main object of the invention is to provide an improved switch of compact construction adapted to complete a variety of desired connections between a number of electrical conductors. A switch of this character is useful for varying tap connections from a transformer winding so as to obtain a desired voltage ratio between the transformer windings, compactness being desirable so that the switch may be located in the same casing with the transformer where the available space is limited. A further object of the invention is to provide an improved switch which may be enclosed in the same casing with a transformer and conveniently operated by means extending through the casing so as to be easily accessible at some outside point. Other objects and advantages will appear.

The invention will be described in connection with the accompanying drawings in which Fig. 1 is a longitudinal sectional view of one embodiment of the invention; Fig. 2 is a cross section on the line 2—2 of Fig. 1; Fig. 3 is a view similar to Fig. 2 but on a reduced scale and showing the movable parts of the switch in a different position; Fig. 4 is a diagrammatic view indicating how the switch may be connected to vary the effective number of turns in a transformer winding; Fig. 5 is a longitudinal view, partly in section, of another embodiment of the invention; and Fig. 6 is a sectional view on the line 6—6 of Fig. 5.

In the form of switch shown in Figs. 1 to 4 inclusive, a plurality of spaced conducting rods or terminals 1, 2, 3, 4, 5, 6 and 7 are supported by a pair of insulating end plates 8 and 9. Seven such rods or terminals are shown but this particular number is not necessary and it will be apparent that a larger or smaller number may be used if desired. These terminals surround a central shaft 10 carried in bearings in the end plates 8 and 9. A binding member or connector 11 is rotatably supported about an offset portion of the shaft 10 and

serves to complete desired connections between the terminals 1 to 7. The connector 11 is divided longitudinally into two sections which are pressed yieldingly toward each other and about the offset portion of shaft 10 by bolts 12 with springs under their heads. The connector 11 is retained in place on the shaft 10 by washers 13 and 14 and a cotter pin 15 on the shaft at each side of the connector. Figs. 1, 2 and 4 show the connector 11 as connecting the two terminals 1 and 4. It will be noted that in this position, the axis of the connector 11 is tangent to the path of the offset portion of the shaft 10, this path being indicated by the circular broken line 16 in Figs. 2 and 3. The springs on the bolts 12 press the two sections of the connector 11 tightly against the terminals so as to assure good contact therewith.

The switch is operated by rotating the shaft 10, the two ends of the connector 11 being shifted alternately from one terminal to another. Starting with the connector 11 in the position indicated in Figs. 1, 2 and 4, clockwise rotation of the shaft 10 at first moves the right-hand end of the connector 11 further onto the terminal 4 and its left-hand end off the terminal 1. The right-hand end of the connector 11 must remain in engagement with the terminal 4 but as soon as its left-hand end leaves the terminal 1 it is free to follow a path determined by the circular movement of the offset portion of the shaft 10. The position of the connector just after leaving the terminal 1 is indicated in Fig. 3. As the shaft 10 is further rotated, the left-hand end of the connector 11 will continue to describe a curved path which is convex toward the shaft 10 and the terminal 4 until finally this left-hand end of the connector 11 will move onto the terminal 7, the axis of the connector 11 then being again tangent to the path 16 of the offset portion of the shaft 10. A connection is now established through the switch between the terminals 4 and 7.

Each step in the operation of the switch is similar to the one just described. For instance, a still further clockwise rotation of the shaft 10 will at first move the left-hand end of the connector 11 further onto the terminal 7 and its right-hand end off the terminal 4. The right-hand end of the connector 11 will then move in a curved path which is convex toward the shaft 10 and the

terminal 7, the connector finally reaching another position tangent to the path 16 of the offset portion of the shaft 10 and with its right-hand end on the terminal 3. This 8 establishes a connection through the switch between the connectors 7 and 3.

The different terminal connecting positions of the connector 11 are shown by broken lines in Fig. 4 which indicates diagrammatically how the switch may be used to change tap connections from a transformer winding in order to vary the ratio of transformation. The transformer has two windings 17 and 18, the winding 18 being 10 formed in two main sections from which tap leads are connected to the terminals of the switch. The position of the switch connector shown in Fig. 4 is such that the two inside end tap leads are connected through 15 the switch so that the entire winding is in circuit. It is obvious that by operating the switch as has been already described, small tap sections will be cut out of circuit alternately from the two main sections of the 20 winding 18 and thus the effective number of turns in the winding 18 will be reduced. By operating the switch in the opposite or counter-clockwise direction, the small tap sections of the transformer winding will be 25 cut back into circuit alternately in the two main transformer winding sections and thus the effective number of turns in the winding 18 will be increased. Stops 19 and 20 are provided at the terminals 1 and 5 respectively 30 so that the connector 11 cannot pass beyond the limiting positions in which either all the tap sections of the transformer winding 18 are connected in series or all these tap sections are cut out of circuit. 35 The pressure due to the spring bolts 12 between the contact surfaces of the terminals and the two sections of the connector 11 increases the capacity of the switch and is therefore desirable during such time as 40 the switch is carrying current. While the position of the connector 11 is being changed, however, it is of advantage to eliminate or reduce this pressure and the friction which it causes between the contact 45 surfaces. One of the objects of the invention is to provide a structure which shall possess these advantages. Pins 21 projecting from each section of the connector 11 rest against the peripheries of the washers 50 13 which are keyed to the shaft 10. Oppositely disposed depressions or grooves in the peripheries of these washers 13 are so located as to be directly under the pins 21 when the connector 11 is in any one of its 55 terminal connecting positions. This is shown clearly in Fig. 2. The depressions are just deep enough to permit the sprung bolts 12 to draw the contact surfaces of the connector 11 tightly against opposite sides 60 of the terminals. As the shaft 10 is ro-

tated to shift one end of the connector from one terminal to another, the washers 13 are rotated with the shaft but the connector is kept from rotating with the shaft and washers by the terminals with which it is in 70 engagement. There is thus relative rotation between the connector and the shaft and washers and this moves the depressions in the washers out from under the pins 21, forcing the pins and the two sections of the connector apart slightly as indicated in Fig. 3. The friction between the connector and terminals is eliminated or reduced so that the connector may move easily to its new position. Just as the connector reaches another 80 terminal connecting position, the depressions in the washers 13 again reach the pins 21 and the spring bolts 12 again draw the connector sections tightly against the terminals. 85

A modification of the invention is shown in Figs. 5 and 6. This form of switch includes a plurality of spaced conducting rods or terminals 22, 23, 24, 25, 26 and 27 supported between a pair of insulating plates 28 and surrounding a central shaft 29 carried in bearings in the plates 28. In Fig. 5, the terminal 24 is removed and parts are shown in section to reveal structure. Six terminals uniformly spaced about the shaft 29 are shown, although it will be apparent that a larger or smaller number may be used if desired. Desired connections between the terminals are made by a connector 30 rotatably supported about an offset portion of the shaft 29 and operable in a manner similar to the manner in which the connector 11 of Figs. 1 to 4 is operated. The connector 30, however, has its contact surfaces 31 all at one side of the operating shaft so as to connect adjacent terminals at one side of the switch instead of terminals disposed at opposite sides thereof. The contact surfaces 31 are resiliently supported by spring arms 32 projecting from the body of the connector 30. The connector 30 is provided with a pair of rigid arms 33 with anti-friction rollers 34 at their outer ends. A pair of rings 35 secured to the end plates 28 have radial grooves adapted to receive the rollers 34 to cooperate with the shaft 29 in shifting the connector 30 between its different terminal connecting positions. A roller 34 and grooved ring 35 are shown at each end of the connector 30 but one of these rollers with its ring may obviously be omitted if so desired. 100

The connector in this form of switch is shifted from one position to another in a manner similar to that in which the connector of the switch shown in Figs. 1 to 4 is shifted. In the position shown in Figs. 5 and 6, the connector is connecting the two terminals 22 and 23. To shift the connector to the position in which connection is 110 120 130

made between the terminals 23 and 24, the shaft 29 is rotated in a clockwise direction. During the first part of this rotation of the shaft 29, the contact surfaces 31 are in engagement with and are held between the terminals 22 and 23 so that the connector is forced to rotate in a counter-clockwise direction, the rollers 34 approaching the radial grooves opposite the terminal 26. Further rotation of the shaft 29 moves the rollers into these grooves and withdraws the contact surfaces from between the terminals 22 and 23. The engagement of the rollers with these grooves now forces the connector to continue to rotate in a counter-clockwise direction and the contact surfaces 31 to approach the space between the terminals 23 and 24. Finally the contact surfaces 31 are moved into this space and forced by a toggle action firmly into contact with the terminals 23 and 24, the rollers 34 being withdrawn from the grooves and moved into a position midway between the grooves opposite the terminals 26 and 27. This operation may be repeated to shift the connector to its next terminal connecting position between the terminals 24 and 25. It is obvious that by rotating the shaft 29 in the opposite or counter-clockwise direction, the connector will be shifted in a clockwise direction opposite to that just described; for instance, from the terminals 22 and 23 to the terminals 27 and 28.

What I claim as new and desire to secure by Letters Patent of the United States, is,—

1. A switch including a plurality of terminals, a terminal connecting member having surfaces for contact with said terminals, and means for supporting said connecting member and for moving it to carry one of its contact surfaces from one terminal to another in a curved path convex toward said supporting means and in a direction along said path opposite to that of said supporting means.

2. A switch including a plurality of terminals, a rotatable shaft, a terminal connecting member rotatably carried by said shaft and having surfaces for contact with said terminals, the portion of the shaft carrying said connecting member being offset, whereby a contact surface of said connecting member may be withdrawn from a terminal by rotation of the shaft, and means for guiding said connector to direct said contact surface from one terminal to another during rotation of the shaft.

3. A switch including a plurality of terminals, a rotatable shaft having an offset portion, a terminal connecting member rotatably carried by the offset portion of said shaft and having a surface for contact with a terminal, and means for causing said connecting member to rotate during rotation of the shaft to transfer said contact surface from one terminal to another in a direction around the shaft opposite to that of the shaft.

4. A switch including a plurality of terminals, a rotatable shaft having an offset portion, a terminal connecting member rotatably carried by the offset portion of said shaft and having a surface for contact with a terminal, and means for guiding said contact surface from one terminal to another during rotation of the shaft and in a direction around the shaft opposite to that of the shaft.

5. A switch including a plurality of terminals, a terminal connecting member having opposed contact surfaces, means for pressing said surfaces against opposite sides of a terminal, means for transferring said contact surfaces from one terminal to another, and means for separating said surfaces to reduce friction with the terminals during transfer.

In witness whereof, I have hereunto set my hand this 10th day of Jan. 1923.

LOUIS F. BLUME.
